S. C. MARKATOS

HAT DRIER

Filed June 14, 1923

INVENTOR.
SPIROS C. MARKATOS
BY *Richard Brown*
ATTORNEY.

UNITED STATES PATENT OFFICE.

SPIROS C. MARKATOS, OF NEW YORK, N. Y.

HAT DRIER.

Application filed June 14, 1923. Serial No. 645,476.

To all whom it may concern:

Be it known that I, SPIROS C. MARKATOS, a citizen of the United States, residing at New York, in the county of New York and State of New York, have invented certain new and useful Improvements in Hat Driers, of which the following is a specification.

This invention relates to hat drying chambers and more particularly to a novel and improved drier designed for installation on a conventional type of hot water boiler whereby advantage may be taken of heat radiation so that the drier may be utilized without any additional heating arrangement.

One of the objects of my invention is to provide a hat drier or chamber which can be conveniently mounted on the top of a conventional hot water boiler including provision for conducting steam to the top of the drying chamber so that the heat therein may be uniform throughout and at the same time afford means for supporting and heating a conventional type of sand bag used in hat blocking and pressing art.

A further object of my invention is to provide an annular hat drier or chamber of a diameter to permit of its installation on the top of the conventional hot water boiler and provided with a sliding front closure or door including a steam coil in the top of said chamber so that the heat generated will be conducted uniformly throughout the same and thus avoiding any auxiliary heating device so that the cost of operation is reduced to a minimum.

To enable others skilled in the art to fully comprehend the underlying features of my invention that they may embody the same in the various modifications in structure and relation contemplated, drawings depicting a preferred form have been annexed as a part of this disclosure and in such drawings, similar reference characters denote corresponding parts throughout all the views, of which;

Figure 1 is a perspective view showing the drying chamber installed on a conventional type of hot water boiler.

Figure 2 is an enlarged sectional view illustrating the interior of the chamber and the coiled heating arrangement.

Figure 3 is a sectional view taken substantially on the line 3—3 of Figure 2.

Referring now to the drawings, wherein

like reference characters designate corresponding parts throughout the several views, 5 designates a conventional type of hot water boiler usually heated by gas to generate steam and commonly used in the pressing and steaming and blocking hats as illustrated and described in my co-pending application, Serial Number 644,980, filed June 12, 1923. Connected to the hot water boiler 5 in my system, I provide an outlet or pipe connection 6 for attachment to a casting 7 whereby the steam may flow through a foot operated valve controlled mechanism, not shown, but described in my co-pending application above referred to.

In order to utilize the heat generated from the top of the hot water boiler 5, I have devised a drying chamber having an annular main body 8, the bottom edge 9 of which is crimped to an annular flanged ring 10 and soldered to an annular extension 11, the diameter of said extension being just slightly larger than the diameter of the boiler 5 so that the chamber may be slipped over the top 12 and held frictionally thereby in the manner clearly shown by Figures 1 and 2 of the drawing. It is of course understood that the bottom of the extension 11 is open and consequently, as the heat radiates upwardly, the same will pass into the drying chamber to the hat or hats placed therein. Within the dome-shaped top 13 of the body 8, I have provided an endless circulating coil 14 having a lead or pipe 15 to the hot water boiler and a second lead or outlet 16 to the pipe connection 6 so that the steam entering the coils may pass outwardly through the casting 7 and to the valve when the said valve is opened. It will thus be seen that not only will the heat confined within the coil radiate downwardly, so as to produce a uniform temperature within the chamber, but that the top of the dome will be heated sufficiently to retain the heat in a sand bag 17, used in the hat blocking, pressing and steaming operation.

The front of the body 8 is further provided with a guideway 18 for a segmental sliding closure 19, which may be opened so as to permit access to the interior of the drying chamber. The partitions for supporting the hat to be dried, comprise a plurality of horizontal rods 21 preferably soldered or secured in any well-known manner to the interior of the chamber and while

I have shown but two partitions for this purpose, it will be readily recognized that any number of such compartments may be provided, depending upon the size of the 5 chamber.

While I have illustrated and described my invention with some degree of particularity, I realize that in practice various alterations therein may be made. I therefore 10 reserve the right and privilege of changing the form of the details of construction or otherwise altering the arrangement of the correlated parts without departing from the spirit of the invention or the scope of 15 the appended claims.

Having thus described my invention, what I claim as new and desire to secure by United States Letters Patent is:—

1. A hat drier comprising an annular 20 chamber having a reduced lower extension and open bottom adapted to fit over the top of a hot water boiler, a closure for said chamber and a plurality of hat supports dividing the chamber into compartments ac- 25 cessible through the closure.

2. A hat drier comprising a boiler, an annular chamber having a reduced lower extension of a diameter to frictionally engage and fit over the top of said boiler, a guide and a sliding closure slidable therein for said chamber, hat supporting members dividing the chamber into a plurality of compartments and means in the top of the chamber to radiate heat generated within the top of the boiler. 30

3. A hat drier comprising a boiler, an annular chamber having a reduced lower extension and open bottom of a diameter to frictionally engage and fit over the top of said boiler, a curved guide and a seg- 35 mental closure slidable therein for the chamber, horizontal hat supporting bars dividing the said chamber into a plurality of compartments accessible through the closure and a heating coil in the top of the chamber in communication with the top of the boiler. 40

In testimony whereof I affix my signature.

SPIROS C. MARKATOS. [L. s.]
